UNITED STATES PATENT OFFICE

2,371,421

WOODEN ROOF

John F. Blaski, Chicago, Ill.

Application September 11, 1942, Serial No. 457,994

2 Claims. (Cl. 108—23)

My invention relates to wooden roof and method of making the same and contemplates a plurality of wooden trusses, which, for lack of a better term, will be herein referred to as box-like or of boxlike form. The trusses are laterally spaced one from another, and the intervening spaces between them are closed by plywood panels to complete the roof structure.

Generally speaking, the invention contemplates the construction of boxlike wooden trusses having roof and ceiling plates of plywood, with pipes constituting the struts arranged along the side margins of the plates, so that a completed truss will have as integral parts a roof portion and a ceiling portion.

An object of my invention is to provide a wooden roof truss with plates formed of plywood panels.

Another object of my invention is to provide a wooden roof truss with plates of plywood panels and pipelike struts connected along the side margins of the plates.

A further object of my invention is to provide a wooden roof truss with upper and lower chords of plywood panels which perform the double function of chords for the truss and form permanent roof and ceiling members.

A still further object of my invention is to provide a wooden roof truss having upper and lower chords of plywood panels which are connected together in lapping end-to-end relation, with the overlapping ends of the several panels being those ends which are farther from the mid-length of the truss.

My invention has for an additional object the provision of angle brackets for attachment of pipelike struts to plywood plates.

Another object of my invention includes the provision of clip means having prongs entered in the lapping surfaces of the panels as a means for preventing relative movement of the lapped ends of the panels.

An additional object of my invention is to provide a wooden roof comprising a plurality of trusses laterally spaced from one another with the intervening spaces bridged by plywood panels.

An additional object of my invention is to provide a roof comprising a plurality of laterally spaced trusses with intervening spaces bridged by plywood panels arranged with the panels of the roof boards overlapping the roof panels of the trusses.

An additional object of my invention is to provide a wooden roof structure comprising boxlike trusses having plates formed of plywood panels

constituting roof boards and the ceiling member of the trusses with the intervening spaces between the trusses bridged by plywood panels, with the bridging panels of the ceiling overlying the ceiling panels of the trusses.

Another and further object of my invention is to provide a light-weight wooden roof truss construction in which plywood panels are used as the chords of the truss and which, in addition, form the roof and ceiling boards of the truss, thus reducing the amount of necessary material below that needed in a roof construction wherein laminated rafters are used as chords and separate roof and ceiling boards are used to complete the roof and ceiling respectively.

A further object of my invention is to provide a wooden roof truss construction in which the usual laminated rafters are replaced by plywood panels which serve the double purpose of chords and covering material.

The above, other and further objects of my invention will be apparent from the following description and accompanying drawings.

The accompanying drawings illustrate an embodiment of my invention and indicate the manner of practicing my method, and the views thereof are as follows:

Figure 1 is a side elevational view of a truss embodying the principles of my invention and constructed in accordance with my method.

Figure 2 is a plan view of a row of plywood panels secured together in end-to-end relation and constituting one of the plates or chords of the truss.

Figure 3 is an enlarged fragmental section taken through two adjacent trusses, showing the manner of construction of the trusses and also the manner of securing the bridging panels to adjacent trusses to complete the roof.

Figure 4 is a fragmental plan view of the lapping ends of two of the panels of a truss and showing parts of adjacent bridging panels.

Figure 5 is a vertical sectional view taken in the plane of line 5—5 of Figure 4.

Figure 6 is an enlarged sectional view taken in the plane of line 6—6 of Figure 4.

Figure 7 is a fragmental plan view of a portion of a roof showing the boxlike trusses and bridging members in place.

Figure 8 is a fragmental portion of a side elevational view of a clip employed to maintain the lapping portions of the panels in place.

Figure 9 is a cross sectional view taken in the plane of line 9—9 of Figure 8.

Figure 10 is a vertical sectional view taken

through one end of a truss, showing the manner of securing the ends of the plates in fixed position.

The drawings will now be explained.

A designates a truss shown in side elevation in Figure 1, in partial section in Fig. 3 and in plan view in Fig. 2.

The plate B, forming the roof boards of the truss, and the plate C, forming the ceiling of the truss, are formed by a plurality of plywood panels connected together in endwise relation, as shown in Figure 2, and in lengths sufficient to reach from end to end of the completed truss.

In making the truss of my invention, a plurality of plywood panels 15 are connected together in endwise lapping relation by bolts 16. The central or mid panel 15a of the roof plate B is arranged with both of its ends overlapping the adjacent ends of the adjacent panels 15, as may be seen in Figure 1. The successive panels in the plate are arranged with the ends of the panels farther from the mid length of the truss, overlapping the ends of the adjacent panels. This construction forms a water-tight roof and causes the water or snow to drain off the roof without entering any of the joints between the several panels.

The panels constituting the ceiling plate C are connected together in like manner.

Prior to the time the lapping ends of the panels are bolted together, clips D (Figure 8) are inserted between the lapping faces of the panels. These clips are made of metal with teeth 17 and 18 struck out of the body of the metal, which extend in opposite directions from the body 19 of the strip. These prongs are pointed so as to readily enter the wood of the lapping surfaces as the bolts are tightened. Figure 6 shows one of these clips in position. The purpose of the clips is to serve as a means for preventing relative movement between the lapping portions of the panels, which means is in addition to the connection formed by the bolts.

After the two long strips of panels have been connected together as described, angle brackets E are attached along the plates adjacent their margins. Every bracket is secured in place by bolts 20 passing through the plates and the horizontal flanges 21 of the brackets. Every one of the vertical flanges 22 is provided with a single bolt hole 23.

The struts 24 are formed of pipe, with their ends flattened as at 25, which ends are bored with single bolt holes.

The two long panels, as shown in Figure 2, are then connected together by the pipelike struts in a manner illustrated in Figure 1. The upper ends of the struts are secured to the brackets E of the roof plate by bolts 26, while the lower ends of the struts are connected to the brackets E attached to the ceiling plate C by bolts 27. The angle brackets E are so disposed as to maintain the struts in properly inclined position to function with the plates in creating a rigid truss.

Referring to Figure 10, the end of a plate B is attached to the adjacent end of a plate C by one or more bolts 28. Inserted between the ends of the plates are filler blocks 29 having the outer surfaces suitably inclined to conform to the inclination of the adjacent ends of the plates. Between the inclined faces of the blocks 29, clips D are inserted so that the prongs thereof enter the wood of the adjacent lapping surfaces of the plates and filler as the bolts 28 are tightened.

In this manner the ends of the trusses are secured together against relative movement.

The trusses are then set up in the usual manner, and the ends supported on posts, bed plates or the like, with the several trusses spaced apart, one from another.

The spaces between the adjacent trusses are then filled by rows of plywood panels F secured together in end-to-end relation and laid on top of the adjacent margins of the ceiling plates C of two of the trusses, as shown in Figure 3. The panels F are secured to the plates C by bolts or nails.

A similar row of panels G is then applied to bridge the space between the roof plates B of two adjacent trusses. In order to make weather-tight joints between the rows of panels G and the plates B, filler strips 30 are laid along the side margins of the panels of the plates B. The panels of the row G are laid on top of these filler strips with the end margins of the overlapping panel ends of the bridging rows G aligned with the margins of the overlapping ends of the panels 15 of the plates B, as may be seen in Figure 7. This construction provides a roof of pleasing appearance and without breaking joints between the adjacent rows of plywood panels, as otherwise would be necessary.

To make the joints between the plates B and the bridging rows G weather-tight, the end of one filler 30 on top of the underlapping panel 15 is brought against the end margin of the overlapping panel 15, as may be seen in Figure 6. The underlapping panel 31 of the row G overlaps the overlapping end of the panel 15 of the plate B, a width equal to that of the filler 30. The overlapping panel 32, of the bridging row G (Figure 6), therefore, is spaced above the overlapping panel 15 of the plate B. Interposed between the panels 32 and 15, are other fillers 33. The fillers are held in place by nails or other securing means passed through the lapping side margins of the panels constituting the plates B and the bridging members G.

I have found that this construction provides joints which are weather-tight for all practical purposes.

Referring to Figure 7, it will be noted that the bridging panels G overlap the side margins of the plates B of the trusses, thus providing a roof which is not only weather-tight, but of pleasing appearance.

The provision of the ceiling members formed by the plates C and the bridging of the spaces between the plates C, forms a dead air space which possesses certain insulating characteristics so that a roof constructed in accordance with my invention will be insulated to an extent not possible in a trussed roof of ordinary construction.

By way of example, it might be stated that a roof constructed in accordance with my invention for a span of approximately fifty feet may be made with plywood panels of three-quarters of an inch thickness for the roof plates B and of one-half inch thickness for the ceiling plates C, and the pipelike struts may be made of pipe of one inch outside diameter. A roof constructed of the material of the dimensions given is in all respects strong enough and rigid enough to function under any and all weather conditions.

It will be observed that my invention contemplates the construction of a wooden roof truss using plywood panels for the plates of the truss and pipes for the struts. The roof plate B may

be termed the compression member of the truss, while the plate C may be termed the tension member of the truss. Thus, when loads such as snow, are imposed on the roof, these plywood plates will function in all respects in the same manner and accomplish the same purpose as that accomplished by chords constructed of laminated wood.

Constructing roof trusses in the manner stated reduces the amount of material necessary to complete a roof having a ceiling throughout the extent of the roof, as what amounts to the ceiling in my invention functions as a chord of a truss. The invention affords a complete roof which is covered and sealed and which is completed with a fewer number of board feet of material than would be required if the trusses were made as laminated rafters and roof and ceiling boards used.

The plywood panels of my invention perform double functions—that is to say, they serve as compression and tension members of the truss and as surface coverings.

In carrying out the method of my invention, I connect together a plurality of panels to form a roof plate B, and another plurality of panels to form the ceiling plate C. These panels are then set on edge, the angle brackets applied, and then struts are connected to the angle brackets along the edges of the plates which are then uppermost. The plates are then overturned to present the other edges as uppermost to enable application of the brackets and struts along the opposite margins of the plates. When the struts have been so applied, the ends of the plates are

connected together in the manner heretofore described and as illustrated in Figure 10 of the drawings.

I do not intend to limit my invention to the specific construction shown and described except only in so far as certain of the claims may be so limited, as it will appear to those skilled in the art that changes in the construction and arrangement of the parts may be made without departing from the principles of my invention.

I claim:

1. A wooden roof truss comprising upper and lower chords, said chords consisting of plywood panels connected together to form roof and ceiling members respectively, angle brackets fastened to said chord panels in spaced relation along the side margins thereof, the brackets of the upper chord being staggered endwise of the chord with respect to the brackets of the lower chord, and pipelike struts connected to said brackets to complete the truss.
2. A wooden roof truss comprising a plurality of elongated plywood panels connected together in lapping end-to-end relation and constituting the upper chord member, another plurality of elongated plywood panels connected together in lapping end-to-end relation and constituting the lower chord member, struts connected to each panel of each of said chord members along their side margins and inclined longitudinally of said chord members, the overlapping ends of the said several panels being those ends which are farther from the mid-length of the truss.
